UNITED STATES PATENT OFFICE.

ALMENZER PACKARD, OF HOLGATE, OHIO, ASSIGNOR TO CLARENCE E. RICHHOLT AND CHARLES RICHHOLT, OF HOLGATE, OHIO, DOING BUSINESS AS RICHHOLT BROS.

BASE FOR STUCCO, PLASTER, AND THE LIKE.

Application filed May 29, 1922. Serial No. 564,392.

To all whom it may concern:

Be it known that I, ALMENZER PACKARD, a citizen of the United States, and a resident of Holgate, in the county of Henry and

5 State of Ohio, have made an invention appertaining to a Base for Stucco, Plaster, and the like; and I do hereby declare the following to be a full, clear, and exact description of the invention, such as will enable others skilled in the art to which it appertains to make and use the same, reference being had to the accompanying drawings, and to the characters of reference marked thereon, which form a part of this

15 specification.

My invention has for its object to provide a stucco or plaster base for exterior or interior wall surfaces that may be made exceedingly thin and consequently light in 20 weight, and, moreover, may be formed of material that is light in weight and but slightly moisture absorbent, whereby buildings may be formed that are weather proof from a material that is of light weight, of 25 low cost and exceedingly durable. It, moreover, has for its object to provide a base for plaster or stucco that will expand or contract but little because of changes in thermal 30 conditions and will not expand or contract by reason of moisture.

My invention may be contained in articles that in their details of construction may be varied in form. To illustrate a practical application of the invention I have selected 35 a slab of burnt or fired argillaceous material which may be made thin and consequently light in weight. The slab is illustrated in the accompanying drawings.

Figure 1 of the drawings illustrates a 40 front view of the slab. Fig. 2 illustrates a rear view of the slab. Fig. 3 illustrates a front broken view of a structure in connection with which a plurality of slabs are used in building the structure. Fig. 4 is a sectional view of a part of the structure illustrated in Fig. 3.

In the figures, 1 is the slab which is formed of argillaceous material, preferably of slate clay. The slab is first formed and 45 then fired so as to convert it to brick material. It being formed of clay, it is comparatively light in weight, and moreover may be formed exceedingly thin, which reduces the weight of the slab as a whole.

55 When formed of a slate it may be made

thinner than when formed of ordinary clay, and moreover is less liable to fracture in shipping and placing the slabs in position.

The slab 1 is provided with a plurality of longitudinal corrugations formed by channels 2 and ridges 3. The channels and ridges constitute a means for keying plaster or stucco or similar material used for surfacing the slabs. The slabs also are provided with holes 4 that are preferably located in the raised portions or ridges of the slabs. The holes 4 provide openings through which nails may be inserted and driven to secure the slabs to a part of the structure, such as the walls of a building. The rear 70 of the slab is provided with raised portions 5 that surround the holes 4. The raised portions form a cushioning means for the slab when the nails are driven home, and, moreover, constitute a means whereby the 75 slab may be secured solid to the supporting structure notwithstanding any slight warping or irregularities in the rear surface of the slab, or irregularities in the surface of the material to which the slabs are nailed. 80 The raised portions are crowded against the surface and if a nail is driven too close the material forming the raised portions will be broken down, or if the slab is slightly warped or the surface of the structure covered by one part of the slab is slightly raised the material of the raised portion around the opening will likewise be broken down 85 or will slightly penetrate the material of the wall, or if there is a slightly raised portion 90 of the slab or a slight depression of the portion of the surface of the material of the building covered by the slab the raised portions may be made to contact with the material of the building by reason of the breaking down of raised portions in other parts of the slab, and thus the slab in practically 95 all of its parts may be forced against the supporting structure of the building and the slab held tightly and looseness obviated. 100

The slab, moreover, is provided with a bevelled rear edge 6, particularly at the top and bottom of the slab. When the slabs are placed in position on the building their edges are placed at a short distance apart in the manner well known in brick-laying, and the bevelled edges form a key for the mortar that may be placed between the edges of the slabs or for the plaster or stucco that may be used to cover the slabs. 110

In Figures 3 and 4 is shown, by way of example, the manner in which the slabs may be used. 7 is the studding of a building. 8 is the sheeting that is nailed to the studding in the manner well known in the art. The sheeting may be covered with building paper 8 and the slabs 9 are nailed to the sheeting 8, by the nails 11 that are passed through the holes 4. Certain of the raised portions 5 are broken down so as to secure the slab at practically all points against the sheeting or against the paper.

If desired, mortar may be inserted in the spaces 12 between the slabs. If the building is not covered with stucco it will have the exterior appearance of one that is formed of brick tiling. If desired, the mortar between the edges of the slabs may be omitted and the slabs may be covered with stucco if they are placed on the exterior of the building, or with plaster if placed on the interior of the building. The stucco will be keyed to the slabs by the ridges and recesses formed at the surface of the slabs, and also by the channels formed between the slabs. The slabs thus form a base for the plaster or stucco which will not warp by reason of moisture, or by reason of changes in temperature conditions. Expansion or contraction will be substantially the same as that of the stucco, and consequently the cracks in the stucco will be obviated. The life of the stucco will be greatly extended, while stucco placed on wooden laths or on iron laths will crack and break off in a short

time, which produces an unsightly appearance and which requires the tearing off of the stucco or the like and replacement thereof, either in part or in its entirety. Furthermore, the slabs being formed of clay and particularly of slate clay enables the production of an exceedingly thin slab which will adhere to the stucco or plaster material and consequently an exceedingly durable building is produced of a comparatively light weight material and at a very low cost.

I claim:

1. In a slab formed of a calcined argillaceous material and having channels and ridges and bevelled rear edges for keying stucco, plaster and the like to the slab, and having nail holes formed therein for securing the slab to a structure, and raised portions surrounding the nail holes on the side of the slabs opposite to the side having the channels and ridges.

2. In a slab formed of a calcined slate clay and having channels and ridges and bevelled rear edges for keying stucco, plaster and the like to the slab, and having nail holes formed therein for securing the slab to a structure, and raised portions surrounding the nail holes on the side of the slabs opposite to the side having the channels and ridges.

In testimony whereof, I have hereunto signed my name to this specification.

ALMENZER PACKARD.
